UNITED STATES PATENT OFFICE.

EVANS WOOD, OF TUTTLE, IDAHO.

WATER TANK.

1,422,325.

Specification of Letters Patent. Patented July 11, 1922.

Application filed August 31, 1921. Serial No. 497,327.

To all whom it may concern:

Be it known that I, EVANS WOOD, a citizen of the United States, and resident of Tuttle, in the county of Gooding and State of 5 Idaho, have invented certain new and useful Improvements in Water Tanks, of which the following is a specification.

This invention relates to water tanks especially adapted for use on automobiles.

10 An important object of this invention is to provide a water tank mounted upon the cowl of a motor vehicle and having novel means whereby the water in the cooling system of the engine may be replenished.

15 Further the improved water tank is provided with simple means whereby a quantity of water may be withdrawn from the tank for any desired purpose.

20 A further object is to provide a water supply means which is simple to apply, cheap to manufacture and neat in appearance.

Other objects and advantages of the invention will be apparent during the course 25 of the following description.

25 In the accompanying drawing forming a part of this application and in which like numerals are employed to designate like parts throughout the same,

Figure 1 is a detail sectional view through 30 a motor vehicle equipped with the improved tank.

Figure 2 is a perspective of the tank detached.

In the drawing wherein for the purpose 35 of illustration is shown a preferred embodiment of the invention the numeral 5 generally designates the improved tank which is of cylindrical formation and is secured on the cowl 6 of the vehicle by means of attach-

40 ing bands 7. The end portions of the attaching bands 7 are extended angularly and are apertured for the reception of bolts 9 ex- tended through the cowl and engaged by nuts 4 so that the bands 7 will be drawn

45 firmly about the tank to hold the same in position. The tank may be supplied with water by means of an inlet pipe 10 having its lower end portion provided with an elbow 11 to which a coupling 12 is connected, the 50 said coupling being extended into one end of the tank.

The intake tube 10 may be provided with a screw cap for the purpose of retaining the water when the car is traveling. This screw

cap is provided with a vent hole, through 55 which air may pass into tank when water is being drawn from tank to radiator.

As illustrated in Figure 1 a discharge pipe 12 is extended laterally from one end of the tank and is provided with a branch 14 ar- 60 ranged adjacent the driver's seat so that the valve 15 interposed therein may be readily turned on or off by the operator. It will be seen that the branch 14 which is arranged in spaced parallel relation to the tank may be 65 arranged within convenient reach of the operator so that the valve 15 may be readily turned off or on to control the discharge of water from the tank.

A pipe 16 is extended forwardly from the 70 branch 14 and inclines downwardly and is connected to one of the water conveyors 18 of the internal combustion engine generally designated by the numeral 19. A forwardly directed pipe 16 is also provided with a valve 75 or cock 20 by means of which the supply of water to the pipe 18 may be controlled.

In the operation of the vehicle, the radiator 20 and motor 9 become highly heated through lack of a proper water supply and 80 by the use of this invention an adequate supply of water to the cooling system of the engine is at all times maintained. Water may be supplied to the cooling system either while the vehicle is in motion or while the 85 same is standing.

If desired one end of the tank may be provided with a cock 25 by means of which the water contained in the tank may be drained or by means of which a quantity of water 90 may be withdrawn from the tank for any desired purpose.

Having thus fully described my invention what I claim is:—

1. The combination with a motor vehicle 95 having an internal combustion engine having a cooling system, said vehicle being provided with a cowl, of a tank secured on said cowl, a pipe extended rearwardly from the tank and having a laterally projecting 100 branch, a valve interposed in said branch and arranged within convenient reach of the vehicle operator, a forwardly directed pipe connected to said branch and having a valve, and means to connect the forward end of the 105 pipe to the cooling system of the engine.

2. The combination with a motor vehicle having an engine provided with a cooling

system, of a water containing tank carried by the motor vehicle at a point above the plane of the engine, a pipe extending from said tank and having a branch, a valve interposed in said branch and arranged within 5 convenient reach of the vehicle operator, a second pipe extending forwardly from said

branch, and means whereby to connect the forward end of the pipe to the cooling system of the engine, whereby water may be supplied to the cooling system from said tank.

EVANS WOOD.
